PAUL O. UNGER, OF SYRACUSE, NEW YORK, ASSIGNOR TO MCMILLAN BOOK COMPANY, OF SYRACUSE, NEW YORK, A CORPORATION OF NEW YORK.

COVER FOR BOOKS, BINDERS, AND THE LIKE.

Application filed December 13, 1924. Serial No. 755,734.

This invention pertains to covers for books and binders, and is more particularly intended for use with loose leaf binders, though in no sense restricted thereto. Stated in general terms, the invention consists in a cover comprising two cover-boards; an intermediate back member formed of sheet steel or other sufficiently strong and rigid material; and a flexible connection for said boards and back member, consisting of tough, strong material or fabric such as leather, canvas, duck, or the like, portions of which pass alternately to opposite sides of the back member and, preferably, also to opposite sides of the cover-boards. To enable such passage of these portions alternately to opposite faces of the parts, the flexible material, if in the form of a single integral sheet, is transversely slotted inward from its longitudinal edges and in its mid portion; or in the case of two sheets, is transversely slotted inward from either or both edges. The slits in the different portions of the flexible member may be in alinement or offset, as preferred. Where the slits extend to the outer edges of the flexible sheet, they produce a series of board-attaching flaps or portions, whether a single flexible sheet or two sheets be employed; but in the case of the integral sheet slotted at its edges and in its mid-portion, the mid-portion is made by the slits to constitute a series of parallel bands between which the back member is passed and held.

The flexible sheet, or the flaps and bands thereof, may be glued, cemented, riveted, or otherwise made fast to the back member and to the cover-boards. In some cases the flaps or board-attaching portions may be left unslotted and applied to one face only of the cover-boards, preferably the inner face. It is likewise practicable to divide the flexible sheet into a series of distinct bands by cutting completely across the same from one longitudinal edge to the other, or to employ strips woven of suitable width, cut to length and laid side by side, in which latter case successive bands would pass respectively from the inner face of one cover-board over the outer face of the back member to the inner face of the other cover-board, and from the outer face of one cover-board over the inner face of the back member to the outer face of the other cover-board. Whether integral or otherwise, the flexible element constitutes in effect one transversely slotted sheet.

By reason of alternate bands passing across opposite faces of the back member, said member is held securely in place, and stress upon one end or section of any given band will cause the opposite end of such band and the cover-board to which such other end is secured, to draw against the edge of the back member, and hence to offer great resistance to being loosened or detached from said back member or from the cover-board. The holding capacity of the bands or sections is of course further enhanced or insured by cementing or otherwise securing them to the back member. Similarly, by carrying the board-attaching sections or flaps alternately to the inner and outer faces of the cover-boards, tendency of the boards to strip off or pull clear of the flexible sheet, or vice versa, is resisted and prevented. This firm and secure mode of holding the back member and attaching the cover-boards is of great importance in the case of books and binders designed to hold a large number of sheets, signatures, pamphlets, catalogues, or the like, and particularly such as are consulted and handled by the general public and frequently subjected to rough usage.

The back member is preferably of curved form in cross section, but this is not essential, and I do not mean to restrict myself to such form.

The finish of the cover may be whatever desired within the ordinary range of the book-binder's art, the invention residing in the parts and features above noted.

The accompanying drawings illustrate the construction in a form intended more particularly for loose leaf binders, and hence show the back member provided with eyes or loops and clips or tongues to facilitate attachment to, or of, other parts making up such binder. In these drawings:

Fig. 1 is an inner face view of a cover laid open and having both the mid-width portion and the marginal or flap portions of the flexible sheet divided, the board-attaching portions so formed being carried respectively to the inner and outer faces of the cover-boards;

Fig. 2, a cross section on the line 2—2 of Fig. 1;

Fig. 3, a fragmentary view of the flexible sheet showing the dividing lines extending across the mid and lateral portions in alinement with each other;

Fig. 4, a similar view showing the divisions of the flaps or board-attaching portions slit on lines intermediate of or in staggered relation to those of the mid-portion;

5 Fig. 5, an outer face view of a cover laid open, showing the flexible sheet made of two sections, each having a continuous board-attaching portion and a divided band forming successive bands of each section being carried alternately to opposite faces of the back member, those of one section alternating with those of the other on both faces of the back member and hence covering both faces thereof;

15 Fig. 6, an enlarged transverse section on the line 6—6 of Fig. 5;

Figs. 7 and 8, fragmentary elevations of the two sections of the flexible sheet shown in Fig. 5;

20 Fig. 9, a view similar to Fig. 5 but showing the bands on the outer face of the back member divided mid-way between the board-attaching sections;

Fig. 10, an enlarged cross section on the 25 line 10—10 of Fig. 9;

Fig. 11, a view of the flexible sheet slit or divided in its mid-width portion, and adapted to have the back member threaded over and under successive bands thereof; 30 and Fig. 12, a fragmentary face view of the cover shown in Fig. 11, but with the outer or board-attaching portions of the flexible sheet divided, alternate bands of each such portion being carried to opposite faces of the 35 cover-boards.

In these drawings, 1 and 2 designate respectively the two cover-boards; 3 the intermediate back member; and 4 the flexible sheet or element as a whole, said flexible element 40 constituting the connection between the cover-boards, the flaps or board-attaching sections of the flexible sheet being designated in Figs. 1 to 4 inclusive by the numerals 5 and 6, and the intermediate or connecting bands which are carried across opposite faces of the back member 3 being designated respectively by the numerals 7 and 8. It will be noted on referring to Figs. 1 and 2, that the flaps or board-attaching sections 5 of the 45 flexible sheet or element 4 are secured to the outer faces of the cover-boards 1 and 2, while the intermediate bands 7 are carried across the inner face of the back member 3; and that the corresponding flaps or board-attaching sections 6 are secured to the inner faces of 50 said cover-boards, while the intermediate bands 8 of such flexible sheet are carried across the outer face of said back member 3.

By reason of this arrangement the flexible 60 material is carried in opposite directions across and in contact with the longitudinal edges of the back member, as seen in Fig. 2, so that stress or pull upon either end of any flap or board attaching section 5 or 6 will be 65 resisted by the secure attachment to the back

member 3 of the intermediate bands 7 or 8, and if the attachment to such back member be loosened, stress on such bands will draw the cover-boards against one or both edges of said back member. Similarly, any stress 70 upon either cover-board tending to pull it away from the board-attaching sections 5 will be resisted by the opposed sections 6 securely attached to the opposite face of the cover-boards, and conversely, any stress or 75 pull tending to pull the cover-boards loose from the board-attaching sections 6 will in like manner be resisted by the sections 5.

As shown in Figs. 1 and 2, the back member 3 is provided with inwardly projecting loops, 80 eyes or staples 9 and spurs or lips 10, cut and pressed inward from the body of the back member, and serving as a convenient means of attachment to, or of, the sheets, signature, pamphlet, or catalogue-holding parts of the 85 complete book or binder. These loops or eyes 9 and spurs 10 are such as are commonly used in loose leaf binders now in extensive use, but are illustrated to show a cover sufficiently complete for use in or with present 90 binders or bindings.

In Figs. 5 and 6 the cover-boards and the back member are again respectively designated by the numerals 1, 2 and 3, the back member being provided with the loops or eyes 9 and spurs 10. 4^a designates the flexible sheet or element, which is here shown as divided into two main portions the outer or marginal portions of which constitute the board-attaching sections which are secured to the cover-boards in any convenient manner, while the remaining portions constituting the mid-field of the complete or two-part sheet 4^a, are slit to form bands 11 and 12, projecting respectively from the two sheet sections 4^a. The bands 11 and 12 of each sheet section are carried in alternation to the inner and outer faces respectively of the back member 3, and are alternated on each face of said back member so that if the topmost band 11 of one sheet section 4^a be carried across and secured to the outer face of the back member 3, as indicated in Figs. 5 and 6, the uppermost band 12 of the other sheet section 4^a will be carried across the inner face of said back member in alignment with said band 11, and so on for successive bands throughout the length of the back member. This alternation will occur on both the inner and the outer faces of the back member 3, but in reverse order as indicated in Figs. 7 and 8, which show respectively the left and right hand sections of the flexible sheet 4^a, the relative positions of the bands 11 and 12 being indicated by legends thereon, and it being understood that the bands of the two sections lie in overlapping relation in the completed cover on opposite faces of the back member.

Fig. 9 shows another embodiment of the same general idea, in which 1 and 2 indicate 130

the cover-boards, 3 the back member, and 4 the integral flexible element or sheet, the marginal or board-attaching sections 4^b of which are securely fastened in any convenient way to the cover-boards. The intermediate portion 5 of sheet 4, which is wide enough to extend across the back member 3 from one to the other longitudinal edge thereof, is transversely divided to form bands 13 and 14 which are respectively carried over the inner and outer 10 faces of said back member, as indicated in Fig. 10. One set of these bands, (14 in the illustrations given), are cross-divided at or about their midlength as shown in Figs. 9, 10, 15 11 and 12, so that the back member 3 may be laid upon the bands 13 of sheet 4, in its proper relative position thereto, while the bands 14, previously opened outward, can by reason of their divided form be laid over the face of 20 said back member opposite that which is placed in contact with the bands 13. This avoids the necessity of threading the back member over and under alternate bands, which involves some little delay and inconvenience, particularly if glue or cement be 25 applied either to the bands or to the back members previous to positioning the latter. Fig. 12 shows the outer or board-attaching sections 4^b of Figs. 9 and 11 transversely divided at convenient intervals and preferably in staggered relation to the dividing lines of the midwidth of the flexible sheet, alternate bands 15 formed by such dividing or slitting of the outer portions of the flexible sheet being carried to the inner and outer faces of the 30 cover-boards 1 and 2, and secured thereto by glue or other adhesive.

It is to be understood that the matter of 40 dividing the board-attaching sections of the flexible sheet or connecting element so that alternate sections may be passed respectively to the inner and outer faces of the cover-boards, is optional with all embodiments of the invention here set forth, and it is not 45 deemed necessary to illustrate it in all figures, since where the covers are to be used with relatively light contents, such attachment to both faces of the cover-boards is not essential. It is, however, a matter of very considerable importance in larger covers and binders, designed to protect an assemblage of leaves, signatures, pamphlets, catalogues, or 50 papers of considerable bulk and weight.

As before indicated, any well-known or 55 usual means of attachment of the flexible element to the cover-boards and to the intermediate back member may be adopted, such as gluing, cementing, riveting, stitching or the like.

It is obvious that two or more bands or two 60 or more flaps or board-attaching portions in immediate succession, might be carried to the same face of the back member or to the same face of a cover-board, without departing from the scope and spirit of my invention. In other 65 words, it is not essential that the bands or the

flaps be carried to opposite faces of the back member or of the cover-boards, in immediate alternation, though such arrangement is preferred. The claims are to be read and understood in accordance with this statement. 70

What is claimed is:—

1. A cover for books and binders, comprising a back member; two cover-boards; and hinges connecting said cover-boards and back member, said hinges being formed of 75 flexible material having a series of separated bands passing across the outer face of the back member in a direction transverse thereto and a second series of bands similarly passing across the inner face of said back member, the portions of the flexible material lying beyond the longitudinal boundaries of the back member being secured to the cover-boards in any convenient manner. 80

2. A cover for books and binders, comprising 85 a back member; and two cover-boards connected therewith by a sheet of suitable flexible material transversely divided in its mid-width portion to form bands between which the back member is held, alternate bands passing over the outer and the inner faces of said member respectively, the flexible sheet having flaps lying outside or beyond the longitudinal edges of the back member and serving as a means of attachment to 90 said boards. 95

3. A cover for books and binders, comprising 100 a back member; two cover-boards, a sheet of flexible material of width sufficient to cover the back member and to extend outward beyond the longitudinal boundaries of 105 said member a distance sufficient to form flaps by which to secure the sheet to the cover-boards, the mid-portion of said sheet being transversely divided into bands over and under which the back member passes in alternation; and means securing the flaps to said cover-boards. 110

4. A cover for books and binders, comprising 115 a back member; two cover-boards; and a sheet of flexible material slitted in its mid-portion to form bands between which the back member is held, the lateral portions of the flexible sheet being each transversely slitted to form a series of board-attaching flaps, some of which are carried to the outer 120 and others to the inner face of the cover-boards, and secured thereto. 115

5. A cover for books and binders, comprising 125 a back member; two cover-boards, a sheet of flexible material divided in its mid-width portion into separate sets of bands which respectively extend across the inner and outer faces of the back member, said sheet extending outward beyond said bands to form flaps for attachment to the cover-boards, said flaps being divided into separate sections which pass alternately to the inner and outer faces of the cover-boards respectively, and are secured thereto. 130

6. A cover for books and binders, comprising a back member; two cover-boards; and a sheet of flexible material secured at its lateral edges to the cover-boards and having its midwidth portion transversely slitted to form bands which pass alternately across the outer and inner faces of the back member, alternate bands being divided in the direction of the length of the back member, whereby the cross-slitted bands may be opened outward from each other and one face of the back member laid upon the unslitted bands, after which the cross-slitted bands may be laid upon the opposite face of the back member.
15. 7. A cover for books and loose leaf binders, comprising a back member; two cover-boards; and a sheet of flexible material of a width to extend across the back member and beyond the longitudinal edges thereof a distance sufficient to form flaps for attachment to the cover-boards, the mid-width portion of said sheet being transversely divided to form bands over and under which, in alteration, the back member is positioned, the outlying marginal portions or flaps of said sheet being similarly divided at points intermediate the dividing lines of the bands in the mid-width portion of the sheet, the sections into which the said flaps are thus divided being passed alternately to the inner and outer faces of the proximate cover-boards and made fast thereto.
25. 8. A cover for books and binders, comprising two cover-boards; an intermediate back member; and a flexible sheet transversely slitted in its mid-portion to form a series of bands which are passed alternately across the

inner and outer faces of the back member, the lateral portions of said sheet being similarly slitted to produce a plurality of flaps which are passed alternately to the outer and inner faces of the cover-boards and secured thereto, those flaps which pass to the outer faces of the cover-boards being in alinement with those bands which pass across the inner face 45 of the back member, and those flaps which pass to the inner face of the cover-boards being in alinement with those bands which pass across the outer face of the back member. 50

9. A cover for books and binders, comprising two cover-boards; an intermediate back member; and a flexible connection between said cover-boards having its opposite marginal portions secured to the respective cover-boards and the intermediate portion divided from the inner edge of one cover-board to the inner edge of the other cover-board to form 55 separate bands, of which successive bands pass respectively across the inner and outer faces of the back member and thus hold said member in place.

10. A cover for books and binders, comprising two cover-boards; an intermediate back member; and a flexible connection between said cover-boards having its opposite marginal portions secured to the respective cover-boards, and the intermediate portion divided and carried in part across the outer face and in part across the inner face of the 65 back member, and secured thereto.

In testimony whereof I have signed my name to this specification.

PAUL O. UNGER.
